UNITED STATES PATENT OFFICE.

THOMAS J. YATES, OF SALEM, MASSACHUSETTS, ASSIGNOR OF ONE-HALF TO SALEM LAUNDRY COMPANY, OF SALEM, MASSACHUSETTS, A CORPORATION OF MASSACHUSETTS.

AUTOMATICALLY-CONTROLLED VALVE MECHANISM.

964,833.

Specification of Letters Patent. Patented July 19, 1910.

Application filed December 2, 1909. Serial No. 530,934.

To all whom it may concern:

Be it known that I, THOMAS J. YATES, a citizen of the United States, and resident of Salem, county of Essex, State of Massachusetts, have invented an Improvement in Automatically - Controlled Valve Mechanism, of which the following description, in connection with the accompanying drawing, is a specification, like characters on the drawing representing like parts.

This invention relates to valve mechanism particularly adapted for use in connection with washing machines for controlling the supply thereto of hot and cold water, so that the water may be introduced into the washing receptacle in a regulated manner and shut off automatically at the desired time.

The principal object of my invention is the production of novel and efficient means for locking the valves in any desired open position, each valve being set independently, together with an instrumentality to unlock the valves and permit closure thereof when a predetermined quantity of fluid has been admitted to the receptacle.

I have herein shown a convenient and efficient device for controlling the operation of the valve-releasing instrumentality, whereby the use of stuffing boxes, floats, and joint-connections with the washing receptacle are obviated.

The valve mechanism itself is so constructed and arranged that the manual opening or setting of the valve is effected with a very slight expenditure of power, such construction and arrangement also preventing hammering, or hammer-blows, when the valve closes.

The novel features of my invention will be fully described in the subjoined specification and particularly pointed out in the following claims.

While my invention is particularly adapted for use in connection with washing machines it is not restricted to such use, as will be apparent hereinafter.

Figure 1 is an end elevation of a washing machine with one embodiment of my present invention applied thereto, one of the valves being shown in closed position while the other is locked in open position, the releasing instrumentality being shown in readiness to operate; Fig. 2 is a detail top plan view of the means for governing the operation of the releasing instrumentality;

Fig. 3 is an enlarged elevation of the valve mechanism, shown in the position illustrated in Fig. 1; Fig. 4 is a left hand side elevation thereof, but in order to avoid confusion locking means for both valves are shown as inoperative, that is, with the valves shut; Fig. 5 is a detail in side elevation showing one of the locking means in position to lock its valve open; Fig. 6 is a sectional detail, on the line 6—6, Fig. 3, taken through one of the valve-chambers, to illustrate the construction of the valve.

Referring to Fig. 1, *a* is a tub or receptacle to which water is to be supplied, such for instance as employed in washing machines for laundry use, the water being introduced to the receptacle at its bottom by a supply pipe *b*, the latter being shown as vertical and extended upward adjacent one of the heads *c* of the receptacle. At the upper end of said pipe *b* is secured a casing *d* which in the present instance has two valve-chambers, one of which, as *e*, is shown in Fig. 6, and pipes or conduits leading from suitable sources of hot and cold water supply are connected with nipples *f* and *g* at the top of the casing, each nipple constituting an inlet to one of the valve-chambers *e*.

The depending extension *h* from the casing *d* is attached to the upper end of the supply pipe *b*, said extension communicating with each chamber *e* and forming the outlet therefor, all substantially of well known construction in apparatus of this general character.

The head *c* has fixed thereto a horizontal rod 1, Figs. 1 and 2, which constitutes a fulcrum for a lever 2, 3 having its shorter arm bifurcated to pivotally support at 4 a receiver 5 having its bottom connected by a rubber or other flexible pipe 6 with an elbow 7 tightly fitted into the head *c* near the bottom of the receptacle *a*, so that at all times the interior of the latter is in communication with the receiver.

Upon the longer arm 2 of the lever is hung a weight 8 which is movable in and out along said arm, to counterbalance the weight of the receiver 5 and a predetermined quantity of fluid therein, it being manifest that whatever may be the level of the fluid in receptacle *a* above the bottom of said receiver the level of the fluid in the receiver will correspond. Consequently the greater

the volume of fluid in the receptacle *a* the greater will be the quantity in receiver 5, with a corresponding increase in weight tending to rock the lever and elevate the 5 free end of its arm 2, so that by adjusting the weight 8 said lever will be rocked when the fluid in the receptacle reaches a predetermined level.

I have herein shown the free end of lever 10 arm 2 as slotted at 9, Fig. 2, to loosely embrace a depending transmitting rod 10 just beneath a collar 11 fixed thereon, so that when the receiver 5 descends the rocking of the lever 2, 3 will elevate said rod 10.

15 The lever and the receiver 5 depending therefrom constitute means governed by the fluid in the receptacle to control the valve-releasing instrumentality, to be described, whereby such instrumentality is caused to operate at a predetermined time to shut off automatically the admission of fluid to the receptacle *a*.

At its upper end the rod 10 is pivotally connected with an arm 12, Fig. 4, of a shouldered bevel-faced detent 13 pivoted at 14 in ears 15 on the extension *h*, a shoulder 16 on the detent engaging a fixed stop 17 to limit descent of the rod 10 and improper positioning of the detent when inoperative.

30 Herein I have shown the releasing member as a vertically movable plate 18 slidably mounted on the face of the casing *d* by means of headed studs 19, the shanks of which pass through elongated longitudinal slots 20 in the releasing member, see Fig. 3, the lower end of said member having a depending extension 21 provided on its rear face with a lateral shoulder 22 and an adjacent beveled face 23, clearly shown in 40 Fig. 4.

Parallel and frontwardly extended releasing ears 24 are formed on the member 18, for a purpose to be described, the upper end of said member being pivoted at 25 to a 45 lever 26 fulcrumed at 27 on a standard 28 fixed on the top of casing *d*, the lever extending across the latter and at its front end terminating in a handle 29.

A depending link 30 is pivoted to the rear 50 end of lever 26 and extends loosely through a guide 31 on the back of the casing, and between said guide and a nut 32 on the lower end of the link an operating spring 33 is coiled around said link.

55 To set the releasing instrumentality the handle 29 is drawn downward, raising the link 30 and compressing the spring 33, and simultaneously the member 18 is depressed, the beveled face 23 wiping over the corresponding face of the detent 13 and swinging the latter back until the shoulder of the detent can swing forward above and in holding engagement with the shoulder 22 carried by the releasing member 18. The 60 detent now retains and holds said member 18

in set position ready to operate, the compressed spring 33 acting to elevate the releasing member and thereby cause it to perform its proper function the instant the detent 13 is rendered inoperative. Manifestly 70 this will occur when the transmitting rod 10 is lifted by the action of the fluid-governed controlling means hereinbefore described, and it will be understood that the normal position of the releasing instrumentality, when fluid is being supplied to the receptacle *a*, is shown in Figs. 1, 3 and 4.

A stop 34 on the member 18 is adapted to engage the bottom of the casing *d* when said member is released, to limit the spring-actuated movement of such member and relieve the headed studs 19 from such duty.

Inasmuch as the two valve structures are the same, and likewise the locking means for each valve, it will be necessary to describe in detail but one valve structure and its locking means.

Referring to Fig. 6 the front end of valve-chamber *e* is provided with a suitable stuffing-box 35 through which passes the longitudinally movable valve-stem 36, the latter having grooves or channels 37 formed therein for part of its length and leading from an enlargement the inner end of which constitutes an auxiliary valve 38 having its seat 39 formed in the adjacent face of a piston 40 constituting a part of the main valve.

The piston slides in an open-ended cylinder 41 screwed into the open rear end of the chamber *e*, the outer end of the cylinder being closed fluid-tight by a cap 42 having a socket 43 for the reception of a spring 44, the inner end of the spring bearing against an annular flange 45 on the enlargement of the valve-stem 36. A longitudinal slot 46 105 in such enlargement receives loosely a pin 47 mounted in ears 48 on the piston, one of such ears being shown in Fig. 6.

By the slot and pin connection the auxiliary valve 38 can be moved to and from its seat 39, by the movement of the valve-stem 36, but at the same time the stem is thereby positively connected with the main valve so that the latter can be moved manually to and from its seat.

The spring 44 tends to seat the auxiliary valve and thereby close the channels 37, and said spring also operates to overcome the friction of the moving parts when the main valve closes, the stuffing-box 35 necessarily 120 exerting considerable friction on the valve-stem.

The piston 40 is not fitted fluid-tight in the cylinder 41, but a clearance of about seven one-thousandths of an inch is provided in practice, so that when the main valve is shut the fluid pressure in the outer end of the cylinder maintains the valve shut and also acts with spring 44 to keep the auxiliary valve seated.

The main valve proper is preferably made of rubber or other non-metallic material, in the form of a thick ring 49 held tightly against the front face of piston 40 by the shouldered thimble 50, which is screwed onto the tubular hub 51 of the piston through which the valve-stem slides.

As shown in Fig. 6 the end of the ring valve 49 is tapered, to fit tightly upon the correspondingly tapered, annular seat 52 formed in the end of a sleeve 53 fixedly mounted in the chamber *e* and in practice forming the passage through which the fluid travels from the inlet nipple *f* (or *g*) when the valve is open, and the thimble 50 is provided with guide-wings 54 which slide upon the interior of the sleeve 53, to guide the valve in its movement to and from its seat 52.

20 To open the valve the valve-stem 36 is pushed inward and such movement is independent of the main-valve and its piston until the auxiliary valve 38 is opened, as shown in Fig. 6, thereby permitting the 25 valve-closing fluid pressure in the cylinder 41 to drop, (it being remembered that when the main valve is shut it is held seated by such fluid pressure acting against the outer end or face of the piston 40) and further 30 inward movement of the valve-stem unseats or opens the main valve with very little effort.

As a matter of fact the instant the pressure is relieved at the outer end of the piston the fluid pressure acting on the inner end thereof moves the main valve from its seat 52 and thereby closes the auxiliary valve 38, and thereafter continued inward movement of the valve-stem completes the 40 desired opening of the main valve with very little effort.

Were it not for the reduction of pressure at the outer end of the piston the power required to open the main valve would have 45 to be exerted against the full fluid-pressure, necessitating a great outlay of strength on the part of the operator when ordinary high pressure is utilized in the sources of water supply.

50 No attempt has been made to illustrate the clearance between the piston 40 and cylinder 41 in Fig. 6, because of the impossibility of so doing on a drawing of the size shown.

55 When the main valve is open it has a constant tendency to close because of the action of the spring 44 and also because the fluid pressure in the cylinder 41 acts upon the entire surface of the piston and the outer 60 end of the seated auxiliary valve 38, while there is less pressure on the opposite side, due to the area of the valve-stem 36. Consequently when the latter is unlocked or released from the locking means, to be described, the main valve closes automatically,

but with a slow movement and without any hammer-blow or shock, for as the clearance around the piston is small the entrance of additional fluid into the cylinder 41 as the piston moves forward must be gradual. As 70 a result undue wear of the valve 49 and its seat 52 is obviated.

While the spring 44 is used mainly to overcome the friction of the moving parts still it has some effect in tending to close 75 the valve, but it always insures the seating of the auxiliary valve during closing movement of the main valve.

Should any grit or sediment pass into the cylinder 41 it can be removed by moving 80 the piston back and forth therein by reciprocating the valve-stem, for by the positive connection between the stem and the piston the latter can be moved manually in either direction.

It now remains to describe the locking means whereby the valve is held open to any desired extent during the admission of fluid to the receptacle *a*. Between a pair of ears 55 on the front of casing *d* directly above each stuffing-box 35 I pivot at 56 a radius-bar 57, slotted at its free end to embrace a segmental locking member 58, pivotally connected at 59 with the radius-bar and having a stop-shoulder 60 adjacent hereto. The lower end of the segment 58 is pivotally connected at 61 with the slotted end of a coupling 62 screwed tightly onto the outer end of the valve-stem 36, and I have extended the member 58 below said coupling to constitute a handle 63 for manually operating the valve.

As shown in Figs. 1 and 3 the locking segment 58 moves in a vertical plane, and as the valve-stem 36 is moved in or out the segment 105 100 swings slightly on the pivot 59 and also moves bodily a short distance vertically, up when the valve is opened and down when the valve is closed, as will be apparent from a comparison of Figs. 4 and 5.

The front or convex face of the locking segment is smooth, as shown, and the bodily change in the position of the segment always takes place about the fulcrum pin 56 of the radius-bar as a fixed center.

Upon the pin 56 outside the ears 55 I mount a yoke-like latch 64, which embraces the segment 58, the cross-bar 65 of the latch co-operating with the convex face of the segment at different points, according to the 120 position of the valve.

The cross-bar is shown as provided with a finger-piece 66, by means of which the latch can be moved by hand if desired, and the inner side of each latch has extended 125 laterally therefrom a rigid pin 67. As shown in Figs. 1 and 3 these pins cross the vertical paths of movement of the releasing ears 24 projecting from the releasing member 18, and viewing the right hand locking 130

means, Fig. 3, it will be seen that the pin 67 thereof will always be above its coöperating releasing ear 24, and wholly independent thereof when the releasing instrumentality is set in readiness to operate. In other words there is no coöperation between any part of the valve-locking means and the releasing instrumentality under normal conditions, and coöperation will not be effected until the detent 13 is disengaged from the shoulder 22 of the releasing member 18. When such release is effected, by the rocking of lever 2, 3 as hereinbefore described, the spring 33 causes the instant operation of the releasing member 18 and the ears 24 thereof are brought into engagement with the pins 67, to thereby swing upward the locking latches into inoperative position, Fig. 4, from any operative or locking position which said pins previously occupied.

Supposing that the attendant has set the releasing instrumentality into the position shown in Figs. 3 and 4 by pushing down the handle 2^a, he then grasps and pushes back toward the casing *d* first one and then the other of the handles 63, and viewing Fig. 4, as said handle is pushed back the connected valve is opened to the desired extent, according to the will of the attendant. As the valve-stem 36 slides inward the position of the locking segment 58 changes, as has been described, and as the segment moves with relation to the pivots 56, 59 the latch 64 swings downward of its own weight, the cross-bar 65 sliding over the convex face of the locking segment. The more the valve is opened the lower down will the cross-bar travel along the segment face, and at any point of its travel a line drawn through the latch fulcrum 56 and the center of the cross-bar 65 will be substantially normal to the convex segment face at the point of engagement, so it may be said that the latch positions itself automatically to lock the segment and the connected valve at any desired opening of the latter.

Unlocking of the valve can only be effected by swinging upward the latch until it is positioned as shown in Fig. 4, leaving the locking segment 58 free to be swung forward by the movement of the valve-stem 36 as the valve closes.

This unlocking is effected automatically when an upwardly moving ear 24 strikes and moves upward the corresponding pin 67, as will be apparent, and as each of the locking means is complete in itself and normally independent of the releasing instrumentality one valve can be set wide open and the other one half open, both valves can be set alike, or any variation in the relative setting can be effected according to the requirements of any particular case. In any event, when the required quantity of fluid has been introduced to the receptacle *a* the supply is

shut off automatically, without any attention on the part of the attendant.

The fluid-governed device for controlling the operation of the releasing instrumentality is at all times in plain sight, it is extremely simple in construction and positive in operation, and as it communicates with the lowest part of the receptacle, soap suds or foam cannot interfere with its action.

While for many reasons I prefer to use the controlling device herein shown it will be manifest that other forms of fluid-governed controlling devices may be used in connection with my novel valve mechanism, so that my invention is not restricted to the control of the valve mechanism by any particular form of fluid-governed device.

As the swinging latch frictionally engages and holds in set position the segment of the valve-locking means the point of coöperation of said latch and segment can be anywhere along the convex face of the segment, permitting any desired degree of accuracy in the opening of the valve.

Various changes or modifications may be made by those skilled in the art without departing from the spirit and scope of my invention as set forth in the claims annexed hereto.

Having fully described my invention, what I claim as new and desire to secure by Letters Patent is:—

1. The combination with a receptacle for fluid, and a valve to control the admission of fluid thereto, of means to lock the valve in open position, comprising a segmental member operatively connected with the valve, and a swinging latch to engage and hold the convex face of said member at different points according to the extent of valve opening, a spring-actuated releasing member to engage and move the latch to release the segmental member and permit closing of the valve, a detent to retain the releasing member inoperative, and means governed by the fluid in the receptacle to effect automatically disengagement of the detent and releasing member.

2. The combination with a receptacle for fluid, and a valve to control the admission of fluid thereto, of a locking segment pivotally connected at one end with the valve-stem, a radius-bar pivotally connected with the other end of the segment, a locking latch fulcrumed coaxially with the radius-bar and engaging the convex face of the segment at different points according to the extent of valve opening, to lock the valve in such position, and means governed by the level of the fluid in the receptacle to swing the latch into inoperative position automatically and thereby unlock and permit closing of the valve.

3. The combination with a receptacle for fluid, and a valve to control the admission of

- fluid thereto, of a locking segment pivotally connected at one end with the valve-stem, a radius-bar pivotally connected with the other end of the segment, a locking latch 5 fulcrumed coaxially with the radius-bar and engaging the convex face of the segment at different points according to the extent of valve opening, to lock the valve in such position, a valve-opening handle forming a rigid 10 continuation of the segment, to provide for manual opening of the valve and a corresponding change in the position of the segment, and means governed by the level of the fluid in the receptacle to swing the latch 15 into inoperative position automatically and thereby unlock and permit closing of the valve.
4. The combination with a receptacle for fluid, and a valve to control the admission 20 of fluid thereto, of a locking segment pivotally connected at one end with the valve-stem, a radius-bar pivotally connected with the other end of the segment, a yoke-like latch embracing the segment and fulcrumed 25 coaxially with the radius-bar, the free end of the latch engaging and holding the convex face of the segment at different points according to the extent of valve opening, to thereby lock the valve open in adjusted position, and automatically acting means to 30 release the segment from the control of the latch and thereby unlock the valve when the fluid in the receptacle reaches a predetermined level.
5. The combination with a receptacle for fluid, and a valve to control the admission 35 of fluid thereto, of means to lock the valve in open position, said means including a swinging latch, a spring-actuated releasing member normally disengaged from the latch and movable into position to engage said latch and swing it into inoperative position independently of movement of the valve, to thereby unlock the valve and permit it to 45 close, a detent to restrain the releasing member from operating, and means governed by variations in the volume of fluid in the receptacle to control the disengagement of the 50 detent and releasing member.
6. The combination with a receptacle for fluid, and a valve to control the admission 55 of fluid thereto, of means to lock the valve in open position, said means comprising a member operatively connected with said valve and varied in its position according to the extent of valve opening, and a latch to coöperate with said member and hold it in any of its positions, and means governed by the volume of the fluid in the receptacle 60 and normally disengaged from the latch, to engage and positively move said latch into inoperative position, to release the member of the locking means with which it operates.
7. The combination with a receptacle for 65 fluid, and a valve to control the admission of fluid thereto, of means to lock the valve in open position, said means comprising a member operatively connected with said valve and varied in its position according to the extent of valve opening, and a latch to coöperate with said member and hold it in any of its positions, a releasing instrumentality normally independent of and out of engagement with the locking means and adapted when operative to engage and inoperatively position the latch, and means to render operative said releasing means when the fluid in the receptacle reaches a predetermined level.
8. The combination, with a receptacle to contain fluid, and a valve to control the admission of fluid thereto, of means for locking the valve in open position and comprising a member pivotally connected with the valve-stem, and a coöperating member pivotally mounted independently of the valve, a device to engage said pivotally mounted member and move it to inoperative position, to thereby unlock the valve, and means governed by the fluid in the receptacle to prevent the operation of said releasing device until the fluid in the receptacle reaches a predetermined level.
9. The combination, with a receptacle to contain fluid, a valve to control the admission of fluid thereto, and a connected valve-stem exposed at one end, of manually-set locking means coöperating with the exposed end of said valve-stem, to lock the valve in open position, a releasing device normally held from engagement with the locking means, and means governed automatically by the volume of fluid in the receptacle to permit said releasing device to engage and move the locking means and cause the same to unlock the valve.
10. In apparatus of the class described, in combination, a receptacle to contain fluid, two valves communicating therewith and connected to sources of fluid supply, automatically acting locking means coöperating with each valve to retain it in adjusted open position when manually moved thereto, a spring-actuated releasing member normally disengaged from said locking means and adapted to engage the two locking means and render them inoperative, a detent to hold the releasing member inoperative, and means governed by the level of the fluid in the receptacle to disengage the detent and releasing member and permit movement of the latter to engage said two locking means and render them inoperative.
11. In apparatus of the class described, in combination, a receptacle to contain fluid, two valves communicating therewith and connected to sources of fluid supply, a locking segment operatively connected with each valve, a latch for and to coöperate with each

segment to permit desired opening of the connected valve and hold it in such open position, and separate means controlled by the volume or liquid in the receptacle to engage the latches and move them into inoperative position relative to their segments, to thereby release the valves.

12. In apparatus of the class described, in combination, a receptacle to contain fluid, two valves communicating therewith and connected to sources of fluid supply, a locking member operatively connected with each valve, a coöperating member to engage the locking member and hold the connected valve in any desired open position, and means controlled by the volume of fluid in the receptacle and normally disengaged from the said coöperating members to engage both of said coöperating members and move them out of operative engagement with their respective locking members, to thereby release the valves.

13. In apparatus of the class described, in combination, a receptacle, a pair of valves to control the admission thereto of separate supplies of fluid, a locking member movable with and also relatively to each valve, an independently mounted latch to cooperate with each locking member at different points thereon, to permit independent setting of the valves in open position and lock them when set, and means controlled by the level of the fluid in the receptacle to move both latches into inoperative position and thereby unlock the valves.

14. In apparatus of the class described, in combination, a receptacle, a pair of valves to control the admission thereto of separate

supplies of fluid, a locking member movable with and also relatively to each valve and having a curved face, a latch to frictionally engage the curved face of each locking member at different points thereon, according to the extent the corresponding valve is set open, to lock such valve open, a releasing member movable between the latches to engage them and release the locking members from control of said latches, permitting the valves to close, and means to prevent operative movement of the releasing member until the fluid in the receptacle reaches a predetermined level.

15. The combination with a fluid-supply controlling valve, of a segmental member operatively connected therewith at one end, a swinging support for the other end of said member, a latch fulcrumed coaxially with the said support and operatively engaging the convex face of the segmental member at different points according to the change in the position of said member to correspond with the extent of valve opening, to lock said valve in open position, and spring-actuated means to engage and move the latch to inoperative position to thereby release the segmental member and permit closing of the valve; said latch when in locking position being substantially normal to the convex face of the segmental member.

In testimony whereof, I have signed my name to this specification, in the presence of two subscribing witnesses.

THOMAS J. YATES.
